A. W. BRIGGS

TRAFFIC STOP

Filed Dec. 21, 1923

Inventor
A. W. Briggs,

By *Philip A. Howell*
Attorney

UNITED STATES PATENT OFFICE.

ARTHUR W. BRIGGS, OF OMAHA, NEBRASKA; CLARA BRIGGS, ADMINISTRATRIX OF THE ESTATE OF SAID ARTHUR W. BRIGGS, DECEASED.

TRAFFIC STOP.

Application filed December 21, 1923. Serial No. 682,070.

To all whom it may concern:

Be it known that I, ARTHUR W. BRIGGS, a citizen of the United States, residing at Omaha, in the county of Douglas and State 5 of Nebraska, have invented certain new and useful Improvements in Traffic Stops, of which the following is a specification.

The invention relates to railroad crossing gates, and has for its object to provide a device 10 of this character which is train operated and comprises shafts disposed at opposite sides of a railway track and provided with U-shaped members normally in a horizontal plane, which U-shaped members are 15 moved to a vertical position through mechanism actuated by a train for preventing vehicles and the like from crossing the track.

A further object is to provide means actuated by the train for returning the U-shaped 20 members to horizontal inoperative position after passing the crossing. Also to provide lights on the U-shaped members so they can be easily observed at night.

A further object is to provide a lever 25 means whereby the gates can be manually operated if desired.

With the above and other objects in view the invention resides in the combination and arrangement of parts as hereinafter set 30 forth, shown in the drawing, described and claimed, it being understood that changes in the precise embodiment of the invention may be made within the scope of what is claimed without departing from the spirit 35 of the invention.

In the drawing:—

Figure 1 is a top plan view of a conventional form of railway crossing, showing the device applied thereto.

Figure 2 is a transverse sectional view taken on line 2—2 of Figure 1.

Figure 3 is a perspective view of the supporting posts for one end of one of the shafts and the securing means.

Referring to the drawing, the numeral 1 designates a conventional form of railway and 2 a roadway crossing said railway at a right angle. Disposed adjacent opposite sides of the railway 1 are spaced ties 3, to 45 the outer ties of which elongated shafts 4 are connected and rotatably mounted in bearings 5, whereby said shafts may rotate. 50 Although ties are described for use as a base for the shafts, it is to be understood that any 55 other suitable foundation may be used.

Shafts 4 may be of any length desired and extend beyond the opposite sides of the roadway 2 and have one of their ends provided with inwardly extending horizontally disposed arms 6, which arms have their free 60 ends provided with pins 7 which extend through elongated slots 8 in transversely disposed rock levers 9, which levers are pivotally mounted at 10 adjacent the under sides of the rails 11 of the railway, and have their 65 inner ends terminating in upwardly and inwardly extending arms 12, which terminate adjacent the inner sides of the rails 11, where they will be engaged by the wheel flanges of the cars of a railroad train or engine, and 70 will be forced downwardly, thereby rocking the levers 10 upwardly at their outer end and moving the arms 6 to a vertical position substantially ninety degrees. The shafts 75 where they cross the roadway 2 are provided with U-shaped portions 13, which portions are normally horizontally disposed and which form a barrier for vehicles crossing the railway when moved to a vertical position upon the approach of a train and a partial rotation of the shafts 4 when the wheel flanges of the train depress the arms 12 of the levers 9. When the U-shaped members 13 are in raised position they form a barrier 80 for preventing vehicles from crossing the 85 track, however for night purposes the U-shaped members 13 are provided with lamps 14 which will be plainly visible to operators of vehicles approaching the crossing.

The ends 15 of the shafts 4 are rotatably 90 mounted in posts 16, and are provided with levers 17, which levers when the shafts are automatically rotated by the train approaching the crossing moves upwardly and outwardly and into engagement with the hooks 95 18 carried by the posts 16, thereby limiting the rotation of the shafts. Levers 17 also form means whereby the shafts may be manually operated if so desired, thereby allowing the barriers to be manually moved to 100 operative or inoperative positions. The shafts 4 outside of the posts 16 are provided with downwardly extending arms 19, which arms have pivotally connected thereto at 105 20 inwardly extending rods 21, which rods 21 extend beneath the rails 11 and are pivotally connected at 21 to the arms 23 of a horizontally pivoted member 24, therefore it will be seen that when the parts are in the normal position shown in Figure 1 an angularly 110

disposed member 25 carried by the last car of a train would pass the restoring pin 26 carried by one of the arms 23, however after the shafts have been rotated ninety degrees 5 in the manner set forth above the pin 26 will be in a position ninety degrees from that shown in Figure 1, and consequently in the path of the angularly disposed member 25 carried by the last car of the train, 10 therefore the member 25 will engage the pin 26 and move the pivoted member 24 to normal position shown in Figure 1, and rock the shafts 4 and the U-shaped members 13 to horizontal position as shown in 15 Figure 1.

From the above it will be seen that a train operated barrier is provided for railroad crossings, which barrier will be moved to operative position by a train upon approaching the crossing and will be restored to normal position by the train after passing the crossing. It will also be seen that manual means is provided whereby barriers may be operated by hand if desired.

25 The barrier elements are maintained in operative positions by the positioning of the U-shaped members 13 in vertical positions which is insured by the limiting arms 17 engaging the hooks 18. It is to be understood 30 that the device is of considerable length,

consequently the barrier elements will be moved to operative position by the engagement of the wheels of the car or train approaching the crossing with the members 12.

The invention having been set forth what is claimed as new and useful is:

The combination with a railway, of railway crossing barriers, said barriers comprising longitudinally disposed rockable shafts at opposite sides of the railway, train actuated levers cooperating with one end of said shafts for rocking said shafts substantially 40 ninety degrees, inwardly extending U-shaped members carried by the shafts and forming barriers, the other ends of said shafts being 45 provided with downwardly extending arms, rods connected to said arms and extending inwardly under the rails, an angularly disposed horizontally pivoted member to opposite ends of which the inner ends of 50 the rods are pivotally connected, a vertically disposed pin carried by said horizontally pivoted member, said pin being adapted to be engaged by a member carried by a train for restoring the U-shaped members to normal horizontal position after the train has 55 passed a crossing.

In testimony whereof I affix my signature.

ARTHUR W. BRIGGS.
